UNITED STATES PATENT OFFICE

144,503

DESIGN FOR A TOY BOAT

T. Barry Hodge, Chicago, Ill.

Application July 18, 1945, Serial No. 120,781

Term of patent 7 years

(Cl. D34—15)

To all whom it may concern:

Be it known that I, T. Barry Hodge, a citizen of the United States of America, residing at Chicago, in the county of Cook and State of Illinois, have invented a new, original, and ornamental Design for a Toy Boat, of which the following is a specification, reference being made to the accompanying drawing, forming a part thereof.

The figure is a perspective view of a toy boat showing my new design. The article presents substantially the same appearance from the side not shown as from the side illustrated in the drawing and the rear thereof is plain.

I claim:

The ornamental design for a toy boat, substantially as shown and described.

T. BARRY HODGE.
